WASHING MACHINE

Michael Phillip Gaultier, St. Paul, and Merrill Laffayette Alexander, Minneapolis, Minn.

Application October 26, 1938, Serial No. 237,036

4 Claims. (Cl. 192—33)

This invention relates to improvements in washing machines, an object thereof being to provide a simple, durable, efficient and relatively inexpensive washing machine employing agitators of the plunger type and having control means for discontinuing and resuming the reciprocation of the plungers, at will, said means, when operated to discontinue the reciprocation of the plungers, being adapted to bring them to rest in elevated position and to hold the same securely in such position.

With the foregoing and other objects in view, which will appear in the following description, the invention resides in the novel combination and arrangement of parts and in the details of construction hereinafter described and claimed.

In the drawings, Fig. 1 is a rear elevational view of a washing machine embodying our invention, the same being shown as attached to a stationary laundry tub; a portion of the tub being broken away and the rear panel of the machine case being removed; Fig. 2 is a detail sectional view, in elevation, taken as on the line 2—2 of Fig. 1; Fig. 3 is a detail sectional view, in elevation, taken as on the line 3—3 of Fig. 1; Fig. 4 is a fragmentary sectional view, in plan, taken as on the line 4—4 of Fig. 1; Figs. 5 and 6 are views similar to Fig. 4 showing certain parts in different positions; Fig. 7 is a detail sectional view, in plan, taken as on the line 7—7 of Fig. 3; Fig. 8 is a detail sectional view, in elevation, taken as on the line 8—8 of Fig. 4; Fig. 9 is a detail sectional view, in elevation, taken as on the line 9—9 of Fig. 5, and Fig. 10 is a detail sectional view, in elevation, taken as on the line 10—10 of Fig. 5.

Reference being had to the accompanying drawings, wherein similar parts throughout the several views are designated by similar reference characters, it will be observed that the illustrated apparatus comprises a washing machine which may be applied to a stationary laundry tub 12 of conventional design having an intermediate partition 13 forming two compartments or receptacles *a*, *b* in the tub structure. The washing machine includes a main cabinet-like section A for the tub receptacle *a* and also an auxiliary cabinet-like section B for the second tub receptacle *b*. The main machine section A carries a wringer C in position overhanging the forward portion of the tub partition 13.

The main section A of the washing machine includes a bed plate 16 which covers the rear portion of tub receptacle *a* and the auxiliary section B includes a bed plate 16 which covers the rear portion of the tub receptacle *b*.

To promote quietness of operation and to render the covering of the tub structure by said bed plates water-tight, gasket strips 17 of soft rubber are applied to the upper edges of the walls

and partition of the tub 12 and it is upon these strips that the bed plates 16 rest.

The main machine section A is equipped with a pair of vertically reciprocable plungers, each indicated in its entirety by the reference numeral 18. These plungers are located side by side and each thereof has a tubular stem 19 guided in a packing gland 20 located near the forward edge of the bed plate 16. Also included in each plunger structure is a vacuum cup 21 provided with an axial boss 22 formed with a concentric groove 23 into which the lower end of the tubular stem 19 is seated, said boss being secured to said stem 19 by means of a fastening pin 24 passing through the boss and the portion of said stem seated therein. Still further included in each plunger structure is a rod 25 having a cylindrical head 26 thereon (Fig. 9) slidably fitted in the tubular stem 19. Threaded into the upper end of the tubular stem 19 and pinned thereto is a cap 27 which is apertured to receive the rod 25. Within said tubular stem 19 are upper and lower helical springs 28, 29, the former encircling the rod 25 and compressed between said cap 27 and the upper end of the head 26, while the latter is compressed between the lower end of said head 26 and the boss 22 of the vacuum cup 21. The upper ends of the rods 25 of the companion plungers 18 are threaded and secured by means of opposing nuts 30 to the opposite ends of a cross-head 31 fitted with upper and lower rollers 32 which travel in a way 33 formed between two upright guides 34, flanged as at 35, to receive said rollers, said guides having their footing on the bed plate 16. Incorporated in the cross-head 31 is a yoke 36 consisting of spaced horizontal rails 37 flanged at their edges, as at 38. The cross-head 31, carrying the plungers 18, is reciprocated vertically by a crank mechanism which, as shown, comprises a crank shaft 39, a wheel 40 thereon and a roller 41 mounted on said wheel. This roller 41 is received between the flanged yoke rails 37 and alternately acts against the same in rolling contact therewith to elevate and depress said cross-head. The crank shaft 39, extending transversely of the bed plate 16, projects into a gear housing 42 and is journaled in bearings in the front and rear walls thereof. This housing is supported upon a hollow pedestal 43 formed as an integral portion of the bed plate 16.

An electric motor 44 mounted on the bed plate 16 supplies power for driving the crank shaft 39. The drive shaft 45 of this motor 44 is connected through a coupling 46 with a main shaft 47 aligned therewith and extending longitudinally of the bed plate 16. This main shaft 47 is journaled in and extends through the gear housing 42 beneath the crank shaft 39 at right angles thereto. Gearing within the housing 42 for

transmitting power from the main shaft 47 to the crank shaft 39 includes a worm 48 keyed to said main shaft. Also included in said gearing is a worm wheel 49 meshing with said worm and loosely journaled on the crank shaft 39. This worm wheel 49 has a front hub which is formed with a recess 50 in its face and constitutes a clutch member 51, a companion clutch member 52 being provided in the form of a sleeve slidably keyed on the crank shaft 39 and formed with a lug 53 adapted to enter the recess 50 in the clutch member 51. For shifting the clutch member 52 into and out of engagement with its companion clutch member 51 and to thereby connect the crank shaft 39 with the driving motor 34 or disconnect the same therefrom, we provide an upright rock shaft 54 the same being journaled in and extending through the top of the gear housing 42. At the lower end of this rock shaft 54 is a depending, eccentric pin 55 occupying position within an annular groove 56 formed externally of the clutch member 52. This pin 55, cooperating with the clutch member 52, shifts said clutch member back and forth when the shaft 54 is rocked, and to rock said shaft, we secure an actuating lever 57 thereto above the gear housing 42. From the foregoing, it will be understood that the plungers 18 may be set into operation by swinging the clutch lever 57 from a neutral position (Fig. 6) to a clutch engaging position (Fig. 4) and that the operation of said plungers may be discontinued by swinging said lever 57 back to starting position.

To house the mechanism supported upon the bed plate 16 of the main machine section A, we provide a case 58 having a body consisting of a front wall and top and end walls formed integrally therewith, said front and end walls being fastened at their lower margins by means of screws 59 threaded into upstanding anchoring lugs 60 cast on the bed plate 16. A back panel 61, completing the case 58 is removably held in place by means of screws 62 passing through its lower marginal portion and threaded into other anchoring lugs 60 on said bed plate. Openings 63 formed in the front wall of the case 58 and openings 64 formed in the back panel 61 provide for the circulation of air through said case to insure proper cooling of the motor 44.

The clutch lever 57 is conveniently operated from a position in front of the machine, by means of a flexible push-pull rod or wire 65 which extends through the front wall of the case 58. Outside of the case, said rod 65 is fitted at one extremity with a finger piece 66, while inside of said case a substantial portion of said rod is guided in a tubular guide 67 to prevent buckling, the inner extremity of the rod being connected with the free end of said clutch lever 57. In addition to the push-pull rod 65, the clutch lever 57 is supplied with spring actuating means which includes a post 68 revolvably supported in the top of the gear housing 42. A link 69, slideable at one end in a horizontal bore in said post 68, is pivotally connected at its other end to the clutch lever 57. A helical spring 70 encircling said link 69 is compressed between the post 68 and an abutment collar 71 on said link. This link 69 is "on center" when the point of its pivotal connection with the clutch lever 57 lies in a plane common to the axes of the rock-shaft 54 and post 68. In said "on center" relation of said link 69, the clutch lever 57 is substantially midway between its two extreme positions and the spring 70 is without effect insomuch

as the swinging of said lever 57 is concerned. However, upon the swinging of the lever 57 by the push-pull rod 65 in one direction or the other beyond said midway position thereof, said link 69 assumes an "off center" relationship and the spring 70 becomes active to urge further movement of the lever 57 in such direction. Said spring actuating device operated yieldingly to complete and maintain the engagement of the clutch members 51, 52 when the lever 57 is swung past "center" in one direction and, likewise, operates yieldingly to complete and maintain the disengagement of said clutch members when said lever 57 is swung past "center" in the reverse direction.

An important feature of the invention resides in a provision whereby clutch disengagement is effected only when the plungers 18 are at the top of their reciprocating cycle of movement, such clutch engagement being attended with the latching of the crank wheel 40 in position to maintain said plungers in such elevated position. This feature is advantageous in that this elevated disposition of the plungers affords ready access to the articles beneath the vacuum cups 21 within the tub 42 and the maintenance of the plungers in such disposition eliminates any danger of injury or annoyance to the user which otherwise might result upon the unpredicted descent of the plungers from an elevated position. Depending from the clutch lever 57 is a socket member 72 in which one end of a lug 73 of suitable composition is lodged at the rear face of the crank wheel 40 is a partially annular concentric abutment 74, the same being slightly less than 360°, the remainder of the circle being occupied by an interrupting recess 75 formed in the crank wheel 40. When the clutch lever 57 is pushed past "center" by the rod 65, the spring 70 alone, or together with the pushing action of said rod, continues such movement of said lever thus shifting the lug 73 toward the crank wheel 40. Arriving at the face of said crank wheel, the lug 73 enters the recess 75 if it happens at the instant to be in registry with said lug, otherwise the lug slidably bears against said partially annular abutment 74 until registry of said recess therewith occurs, whereupon said lug then enters said recess. The parts are so proportioned that the clutch members 51, 52 are disengaged after the lug 73 passes from the plane of the abutment 74 into the recess 75 and said recess is located angularly of the crank wheel so that clutch disengagement by entry of the lug 73 into said recess 75 is effected immediately prior to the arrival of the plungers 18 at the top of their reciprocating path. The leading portion of the recess 75 is formed to provide a shoulder or stop 76 which engages the lug 73 and prevents the unclutched crank wheel 40 from turning counter to its normal direction of rotation under the weight of the elevated plungers 18 and cross head 31. The recess 75 is elongated to provide clearance between the crank wheel 40 and lug 73 after the initiation of the reclutching throw of the lever 57 and until said lug is fully retracted from said recess. To prevent all possibility of jamming and the consequent injury of parts under extreme circumstances, we equip the rock shaft 54 with an arm 77 and the crank wheel 40 with a segmental guard 78 with which said arm cooperates. Said guard, angularly of the crank wheel, is coextensive with the trailing portion of the recess 75. The face of this guard 78 constitutes an abut-

ment 79 which is engaged by the arm 77 when the lug 73 would enter the recess 75 at the trailing portion thereof rather than at its leading portion. When said arm thus engages said segmental abutment 79 the unclutching throw of the lever 57 is thereby interrupted, such interrupting continuing until the partially annular abutment 74 on the turning crank wheel 40 passes the lug 73 and permits it to enter the leading portion of the recess 75. The leading end of the segmental guard 78 is beveled to provide a cam shoulder 80 engageable with the arm 77 to latch the crank wheel 40 against continued rotation when the lug 73 enters the leading portion of the recess 75, this latching action being readily effected due to the little momentum present in the unclutched crank wheel 40 on the upstroke of the plungers 18. When the rod 65 is pulled upon to turn the rock shaft 54 and reclutch the crank wheel 40, said cam shoulder 80 on the guard 78 cooperates with the arm 77 to insure further turning of the rock shaft 54 after clutch engagement and with such promptness that the lug 73 is caused to swing out of the trailing portion of the recess 75 and clear the crank wheel 40.

A gear housing 81 is provided for the wringer C, said housing being cast integrally with a standard 82 which has its footing on the bed plate 16. Also cast integrally with the gear housing 81 is a mounting bracket 83 formed with flanges 84 against which the front of the case 58 is positioned. The wringer C has a mounting head 85, the same being clamped against the front of the case 58 and to the flanges 84 of the mounting bracket 83 by means of bolts 86 extending through said mounting head 85, case 58 and flanges 84. Also extending through the case 58 is the wringer shaft 87 the same being driven, when desired, in one direction or the other through gearing from the driving motor 44. This wringer gearing includes a counter shaft 88 in which a coupling 89 is incorporated, said counter shaft being mounted at one end in the gear housing 42 and at the other end in the gear housing 81. Within said housing 42, the counter shaft 88 has a bevel gear 90 keyed thereto and which meshes with a bevel gear 91 cast integrally with the worm wheel 48, while within the housing 81 said counter shaft 88 is supplied with bevel gears 92, 93 loosely mounted thereon. Meshing with both of said bevel gears 92, 93 is a bevel gear 94 which is pinned to a stub-shaft 95 mounted in said gear case 81 and connected by a coupling 96 to the wringer shaft 87. Feathered on the counter shaft 88 between the two gears 92, 93 is a clutch collar 97 having an annular groove 98 therein which receives an eccentric pin 99 depending from a rock shaft 100 mounted in the cover of the housing 81. Through the medium of the rock shaft 100 the clutch collar 97 is moved from a neutral position into either of two clutching positions, one resulting in the engagement of a lug 101 on the collar 97 with a lug 102 on the gear 92 and the other resulting in the engagement of a lug 103 on said collar 97 with a lug 104 on the gear 93. In one of these clutching positions of said collar 97, the wringer shaft 87 is turned in one direction and in the other of said clutching positions of the collar, said wringer shaft is turned in an opposite direction. To turn the rock shaft 100 and thereby position the clutch collar 97 as desired, we provide a push-pull rod 105 which extends through the front of the case 58 and is supplied with a finger knob 75

106 outside thereof, the inner end of said rod 105 being connected through a link 107 with an arm 108 on said rock shaft 100.

The hollow pedestal 43 on which the gear housing 42 is mounted provides a compartment 109 with a bottom opening therein which is closed by a sealing panel 110 of glass. In said compartment 109 is an electric lamp 111 for illuminating the interior of the tub receptacle a. This lamp 111 may be energized by the electrical circuit with which the motor 44 is connected.

A filler-neck 114 cast integrally with the bed plate 16 is cut away at one side thereof to admit thereto the end of a swinging faucet nozzle of the type usually employed in connection with partitioned tubs. This filler-neck is normally closed by a disc valve 115 carried on a pivoted counter-weighted arm 116, said valve being readily unseated by the force of the water entering the filler-neck 114 and introduced thereinto to be directed thereby into the tub receptacle a.

The tub stopper 117 in the receptacle a may be conveniently removed from the drain opening 118 by means of an upright pull rod 119 slidably mounted in the bed plate 16, said rod being connected at its lower end to said stopper by a chain 120 and supplied at its upper end with a finger button 121.

Except for the wringer C and driving mechanism therefor, the auxiliary machine section B is a substantial duplicate of the construction of the main machine section A, hereinbefore described, and since most of the parts of said auxiliary section B bear the same reference characters as their counterparts in the main machine section A, a repetition of the previous detailed description will be unnecessary. It may be noted, however, that the main shaft 122 of the auxiliary machine section B is connected by a coupling 123 to the main shaft 47 of the main machine section A, said main shaft 47 being extended through the end wall of the case 58 of said main section A. The joint made between the open end of the case 58 of the auxiliary machine section B and the adjacent closed end of the case 58 of the main section A is finished by means of a band 124 so that when said main machine section A is supplemented by said auxiliary section B a unitary appearance is given to the composite structure.

Either or both of the machine sections A, B may be used for sudsing or rinsing according to the nature of the washing liquid contained in their respective tub receptacles. Commonly, the main machine section A will be used for sudsing the articles to be washed and the auxiliary section B will be used in rinsing the suds articles. Thus, in use, the tub receptacle a will be supplied with hot water through the filler-neck 114 of the main machine section A, soap and/or other cleansing compound being added to such water. To the rinsing water similarly supplied to the tub receptacle b, bluing or the like may be added. The articles to be cleaned will be readily introduced into the tub receptacle a beneath the elevated vacuum cups 21, such process being facilitated by reason of the illumination of the interior of said receptacles. After starting the motor 44, the reciprocation of the plungers 18 is started by pulling on the knob 66 of the push-pull rod 65. Thereupon the vacuum cups 21 operate in the well known manner of such instrumentalities to agitate the articles and force the sudsing water through the fabric thereof. To interrupt the operation of the plung-

ers 18, the user pushes upon the knob 66 of the push-pull rod 63 causing said plungers to stop and remain at the top of their reciprocating path. The wringer C, set into operation by means of the knob 166 on the rod 165, may be used to feed the articles from the tub receptacle a into the tub receptacle b for power rinsing which will be accomplished upon manipulation of the knob 66 of the machine section B to set in motion the plungers 18 thereof.

Changes in the specific form of our invention, as herein disclosed, may be made within the scope of what is claimed without departing from the spirit of our invention.

Having described our invention, what we claim as new and desire to protect by Letters Patent is:

1. In combination, a vertically reciprocable element, a drive shaft, a crank shaft having a crank wheel thereon connected with said element and revoluble in one direction to reciprocate the same, a clutch interposed between said crank shaft and drive shaft and including co-acting members, one thereof being movable relative to the other, a rock shaft connected with said movable clutch member and rockable to shift the same reversely to engage and disengage said clutch, a lever on the rock shaft for turning the same forth and back, a lug on said lever, said crank wheel having a concentric abutment at one face thereof and a recess interrupting said abutment and providing a stop shoulder at the leading end of the recess, said lug being adapted to be received in said recess when in registry therewith, otherwise to bear slidably against said abutment until such registry is attained upon the throw of said lever to disengage said clutch, the reception of said lug by said recess allowing completion of the clutch disengaging throw of said lever, said recess being so located in the crank wheel as to permit clutch disengagement substantially at the top of the stroke of said element, said stop shoulder being adapted to engage said lug to prevent counter rotation of the crank wheel, said recess being elongated to provide clearance at the trailing portion thereof for said lug upon the clutch engaging throw of said lever, an arm on said rock shaft, a guard on the crank wheel engageable by said arm to arrest the clutch disengaging throw of said lever when said lug is in registry with said trailing portion of said recess, the leading end of said guard providing a cam co-operating with said arm to latch the unclutched crank wheel against movement in the direction of its normal rotation and further cooperating with said arm to cause it positively to continue the turning of the rock shaft started by movement of said lever in a direction initiating the engagement of the clutch.

2. In combination, a vertically reciprocable element, a drive shaft, a crank shaft having a crank wheel thereon connected with said element and revoluble in one direction to reciprocate the same, a clutch interposed between said crank shaft and drive shaft and including co-acting members, one thereof being movable relative to the other, a rock shaft connected with said movable clutch member and rockable to shift the same reversely to engage and disengage said clutch, a lever on the rock shaft for turning the same forth and back, a lug on said lever, said crank wheel having a concentric abutment at one face thereof and a recess interrupting said abutment and providing a stop shoulder at the leading end of the recess, said lug being adapted to be received in said recess when in registry therewith, otherwise to

bear slidably against said abutment until such registry is attained upon the throw of said lever to disengage said clutch, the reception of said lug by said recess allowing completion of the clutch disengaging throw of said lever, said recess being so located in the crank wheel as to permit clutch disengagement substantially at the top of the stroke of said element, said stop shoulder being adapted to engage said lug to prevent counter rotation of the crank wheel, said recess being elongated to provide clearance at the trailing portion thereof for said lug upon the clutch engaging throw of said lever, an arm on said rock shaft, and a guard on the crank wheel engageable by said arm to arrest the clutch disengaging throw of said lever when said lug is in registry with said trailing portion of said recess.

3. In combination, a vertically reciprocable element, a drive shaft, a crank shaft having a crank wheel thereon connected with said element and revoluble to reciprocate the same, a clutch interposed between said crank shaft and drive shaft, said clutch including co-acting members, one thereof being movable relative to the other, a rock shaft connected with said movable clutch member and rockable to shift the same reversely to engage and disengage said clutch, a lever on the rock shaft for turning the same forth and back, a latch lug on said lever, said crank wheel having a concentric abutment at one face thereof and a recess interrupting said abutment, an end wall of said recess providing a stop shoulder, said latch lug being adapted to be received in said recess when in registry therewith, otherwise to bear slidably against said abutment until such registry is attained upon the throw of said lever to disengage said clutch, the reception of said lug by said recess allowing completion of the clutch disengaging throw of said lever, said recess being so located in the crank wheel as to permit clutch disengagement in an elevated position of said element, said stop shoulder being adapted to engage said lug to prevent rotation of the crank wheel in a direction to lower said element.

4. In combination, a vertically reciprocable element, a drive shaft, a crank shaft having a crank wheel thereon connected with said element and revoluble in one direction to reciprocate the same, a clutch interposed between said crank shaft and drive shaft, said clutch including co-acting members, one thereof being movable relative to the other, a rock shaft connected with said movable clutch member and rockable to shift the same reversely to engage and disengage said clutch, a lever on the rock shaft for turning the same forth and back, a lug on said lever, said crank wheel having a concentric abutment at one face thereof and a recess interrupting said abutment, the leading end wall of said recess providing a stop shoulder, said lug being adapted to be received in said recess when in registry therewith, otherwise to bear slidably against said abutment until such registry is attained upon the throw of said lever to disengage said clutch, the reception of said lug by said recess allowing completion of the clutch disengaging throw of said lever, said recess being so located in the crank wheel as to permit clutch disengagement substantially at the completion of the upward thrust of said element, said stop shoulder being adapted to engage said lug to prevent counter rotation of the crank wheel.

MICHAEL PHILLIP GAULTIER.
MERRILL LAFFAYETTE ALEXANDER.
